UNITED STATES PATENT OFFICE.

JAMES LEWIS KIMBALL, OF SALEM, MASSACHUSETTS, ASSIGNOR TO RUGGLES-KLINGEMANN MFG. COMPANY, OF SALEM, MASSACHUSETTS, A CORPORATION OF MASSACHUSETTS.

PRESSURE-CONTROL APPARATUS.

Application filed July 14, 1922. Serial No. 574,975.

My present invention relates to pressure-control apparatus and is an improvement upon my copending applications Serial #468,684 of May 11, 1921, and Serial 5 #478,033 of June 16, 1921.

The object of my invention is to provide novel apparatus to effect the following advantages:—

First: definite cut-off points for the fluid 10 pressure motor.

Second: means whereby the compensating device may be adjusted to effect a greater or less pressure variation between cut-off points; and

15 Third: means for maintaining the equilibrium of the pressure device and valve-operating member while the valve is being shifted from a pressure or effective position to a neutral or non-effective position.

20 Although the uses of hydraulic operated pressure controllers are numerous and varied, one of the principal applications is the control of air supply to the boiler furnace and for this service it is necessary that the

25 air supply should bear definite relation to the load on the boiler. Boiler pressure is the most direct and unfailing indication of the relation between the boiler load and the furnace output: with every variation in

30 load, there will be a corresponding variation in pressure, and the air supply, when controlled through the entire pressure range of such load variations, will then be in exact relation to the load requirements. A con-

35 trolling device so adjusted that its pressure operating range, between minimum and maximum air supply, shall be in conformity to load variation is, therefore, the first step to successful automatic draft regulation.

40 With such a device, maximum air will be supplied at the load peaks, but not before the peaks are reached.

I attain these objects in a device as shown in the accompanying drawings, in which 45 Figure (1) is a vertical elevation, Figure (2) shows the support or bearing for shaft (25), Fig. (3) shows the compensating attachment which embodies my invention, separated from the machine as a whole, and 50 Figure 4 is a view of a detail.

Referring to the drawings, Figure (1) shows an assembled view of my invention, the same being connected to a damper arm (35) for operating a damper in a boiler flue

(36). The damper is adapted to be closed 55 by the weight (37) on an upward motion of motor piston (11), a cable or chain extending over suitable sheaves (39) and (40) for this purpose. The steam pressure of the boiler is connected at (41).

60 Referring to Figure (1), (1) is a pressure chamber which is closed by a flexible diaphragm (2). A pressure cap (3) is mounted on the atmospheric side of the diaphragm and engages a valve operating member (4). 65 The valve operating member is fulcrumed at (5). Weights (6) are placed on the valve operating member to counteract the predetermined pressure to be maintained in chamber (1). The above elements constitute a preferred embodiment of a pressure-device for operating pressure controlling valve (7). Referring to Figure (3), showing, in section, a preferred embodiment of a pressure-controlling valve, the inlet for 70 fluid pressure is at (8) and the exhaust at (9), port (10) leads to the bottom of motor cylinder (13), and port (12) leads to the top of motor cylinder (13), above piston (11). Controlling valve (7) has cylindrical 75 portions (14) and (15) which control the admission and exhaust of fluid pressure to and from the motor cylinder (13). Piston (11) has piston rod (16) extending through the top cap of the motor. A connecting 80 member (17) is secured to the top of piston rod (16) and provides means for operating the damper. A member (18) is pivoted to valve-operating member (4) at point (19) and is arranged to be rocked by member 85 (20) which has a stationary pivoted bearing (21), see Figure (2). A connection (22) is made between the left hand end of members (18) and (20). The opposite end of member (20) is connected to valve operating 90 member (4) by means of a spiral spring (23). Arm (24) is secured to shaft (25) and has a roll (26) at its upper end. The roll (26) is held in engagement with the adjustable step member (27) by spring 95 (23). The adjustable step member is hinged at (28) to member (29). The member (29) has a rod (30) which connects with piston-rod top (17). It will be seen that members (27) and (29) are connected to and travel up 100 and down with the piston (11).

105 It will be understood that any variation of pressure in the pressure chamber (1)

above or below a predetermined value will impart motion to the valve-operating member. As member (18) is pivoted to member (4) at point (19). As the right-hand end 5 of this member is connected at (31) with valve yoke (32), and as its left hand end is held stationary, such variations in pressure will operate valve (7) to a pressure position which will admit fluid pressure to the 10 motor cylinder (13). Assuming an increase in pressure in chamber (1), the controlling valve will admit pressure to the under side of piston (11) through port (10), and at the same time vent the upper side of 15 piston (11) to exhaust connection. A decrease in pressure will admit fluid pressure to the top of motor cylinder and vent the bottom to exhaust. It will be understood that the exhaust from top of the motor cylinder 20 is to the bottom chamber of the controlling valve and is connected to the exhaust connection through cored passage (33). It will be seen that an increase in pressure will operate the piston (11) in an upward direction and a decrease in pressure will operate 25 the piston (11) in a downward direction.

One of the objects of this invention being to effect a stopping of the piston (11) at predetermined points in its travel, I have 30 arranged a novel adjustable stepped wedge consisting of members (27) and (29), which travels with the motor piston (11) and imparts motion at each step to rock members (18) and (20). This effects a movement of 35 the controlling valve independent of the pressure device. The movement imparted to the operating valve from the movement of piston (11) is always in the direction to return this operating valve to a neutral or 40 non-effective position at each step on member (27). Assuming an increase in pressure in chamber (1), the controlling-valve upper port (10) is opened to pressure and lower port (12) to exhaust. This results in 45 an upward movement of the piston (11), which motion places roll (26) on a higher stepped position on member (27), which gives the necessary motion to rock members (18) and (20) to return the valve (7) to a 50 neutral or non-effective position. In the same way, on a decrease in pressure in chamber (1), the lower port (12) is opened to pressure and upper port (10) to exhaust. This results in a downward movement of 55 the piston (11) and places roll (26) on a lower stepped position, which rocks members (18) and (20) to give an upward motion to valve (7), thereby placing it in a neutral or non-effective position and again bringing 60 the piston (11) to rest.

It will be seen that I have devised novel means for effecting a cut-off at predetermined points in the travel of the piston (11).

As was pointed out in the statement of 65 invention, a pressure-operating range be-

tween minimum and maximum air supply to the boiler furnace which would be in conformity to load variations is essential to successful, automatic, draft regulation, and I have arranged to effect a greater or less 70 pressure variation between limits of travel of piston (11) by adjusting the angularity of members (27) and (29) by means of adjusting screw (34). The effect of increasing the angularity of the step wedge (27) 75 is to retard the movement of the motor piston (11), or, in other words, to produce a wider pressure-operating range acting on diaphragm (2) between the limits of travel of piston (11). It will be seen that if members (27) and (29), which make up the compensating wedge, are so adjusted as to be in a parallel position in relation to one another, the position of the controlling valve (7) 80 will not be changed in the movement of the compensating wedge from a given stepped position to the next succeeding stepped position, and, therefore, no cut-off action could take place. The controlling valve (7), once moved to a pressure position, could not be 85 moved back to a neutral position, and the motor piston (11) would continue to travel from one extreme to the other with very little variation in pressure in chamber (1). A fluctuating load requiring a wider pressure-operating range between minimum and maximum air supply, it will be seen that 90 the compensating wedge (27) can be adjusted so as to provide a suitable pressure-operating range for varying load variations, the object being to so adjust the compensating wedge that maximum air will not be supplied until the load peak is reached. The proper adjustment will be determined 95 by the step action of the fluid-pressure motor. If the motor piston (11) should travel past one of the stepped positions on compensating wedge (27), it would indicate that 100 the load variations on the boiler were too great for the pressure-operating range between minimum and maximum air and that maximum damper opening was being effected before the peak load was reached. The screw (34) should then be adjusted to give 105 a greater angularity between members (27) and (29), so as to effect a stopping of the piston (11) at each stepped position. The time element is also an important factor 110 which calls for adjustment for a greater pressure-operating range between limits of travel, for if the pressure is increasing or decreasing very rapidly, it will be seen that the valve may be moved so far out of its neutral position that the first step action will not 115 return it entirely to a cut-off position and the piston (11) will continue to travel to the next succeeding step, and so on, to its full stroke, without cut-off action. For this reason, it is desirable to adjust for a wider 120 operating range, so as to insure cut-off ac- 125 130

tion at each stepped position. It has been pointed out that the spring (23) holds the roll (26) in engagement with the stepped side of member (27). The principal object 5 of this spring, however, is to maintain the equilibrium of the pressure device and valve-operating member while the controlling valve is being shifted from a pressure or effective position to a neutral or non-effective 10 position. Member (18) being pivoted to the valve operating member (4) any movement from the compensating means imparted at the left-hand end of this member, through connection (22), will have a tendency 15 to depress the valve-operating member downward on an upward movement of the controlling valve, and to raise this member on a downward movement of the valve. The amount the valve-operating member 20 (4) would normally be thrown out of position would depend upon the friction to be overcome in moving the valve from a pressure to a neutral position. It will be understood that the position and tension of 25 spring (23) can be so adjusted that the rocking of member (20) on bearing (21) will not move the valve-operating member (4) out of balance and will permit the full, stepped movement of the compensating ar- 30 rangement to be transmitted direct to the pressure controlling valve to return said valve to a cut-off position. It will be seen by those skilled in the art that I have devised novel and useful means for compensating 35 a fluid-pressure motor to effect a step-by-step movement and have arranged a novel method of adjusting the compensating device to effect air supply to the boiler furnace in conformity to load variation.

40 In accordance with the provisions of the patent statutes I have described the principle of operation of my invention, together with the apparatus which I now consider to represent the best embodiment thereof; but

45 I desire to have it understood that the apparatus shown is only illustrative and is capable of various modifications and that only such limitations shall be imposed as are indicated in the appended claims.

50 I claim:

1. The combination with a fluid-pressure motor, of a pressure device and a controlling valve for operating the motor, an operating member for said valve, means connecting 55 said valve and said operating member, means co-acting between the first named means and the fluid-pressure motor for shifting the controlling valve from a pressure to a cut-off position, and means for adjusting the second- 60 named means to effect a greater or less pressure variation acting on the pressure device for a given movement of the fluid pressure motor.

2. The combination with a fluid-pressure 65 motor, of a pressure device and a controlling

valve for operating the motor, said valve having a neutral position in which it is not effective and two effective positions for operating the fluid-pressure motor, an operating member for said valve, means connecting 70 said valve with the operating member for moving the valve to either of its effective positions, means connecting said valve with the fluid-pressure motor for returning said valve to a neutral position irrespective of the operation of the operating member, and means for adjusting said second-named connection to effect a greater or less pressure 75 variation acting on the pressure device between the limits of movement of the fluid-pressure motor.

3. The combination with a fluid-pressure motor, of a pressure device and a controlling valve for operating the motor, an operating member for said valve, means connecting 80 said valve and said operating member, and means co-acting between the first named means and the fluid-pressure motor for shifting the controlling valve from a pressure to a cut-off position irrespective of the operation of the operating member at predetermined points in the movement of the fluid-pressure motor.

4. The combination with a fluid-pressure motor, of a pressure device and a controlling valve for operating the motor, an operating member movable to different degrees to operate said valve, compensating means between said valve and said fluid-pressure motor for limiting the operation of said motor to a degree corresponding to the degree of operation of said operating member, means co-acting between the compensating means and the operating member for maintaining 95 the equilibrium of the pressure device, and means for adjusting said compensating means to effect a greater or less pressure variation acting on the pressure device for a given movement of the fluid-pressure motor.

5. The combination with a fluid-pressure motor, of a pressure device and a controlling valve for operating the motor, an operating member for said valve, means connecting said valve and said operating member, means co-acting between the first-named means and the fluid-pressure motor for shifting the controlling valve from a pressure to a cut-off position irrespective of the operation of the operating member at predetermined points in the movement of the fluid-pressure motor, and means for adjusting the second-named means to effect a greater or less pressure variation acting on the pressure device for a given movement of the fluid-pressure motor.

6. The combination with a fluid-pressure motor, of a pressure device and a controlling valve for operating the motor, an operating member for said valve, means connecting said valve and said operating member, means co-acting between the first named 130

means and the fluid-pressure motor for shifting the controlling valve from a pressure to a neutral position, means connecting the second-named means and the operating member 5 to maintain a balanced condition of the operating member while said valve is being shifted, and means for adjusting the second-named means to effect a greater or less pressure variation acting on the pressure device 10 for a given movement of the fluid pressure motor.

7. The combination with a fluid-pressure motor, of a pressure device and a controlling valve for operating the motor, an operating member for said valve, means connecting said valve and said operating member, means co-acting between the first-named means and the fluid-pressure motor for shifting the controlling valve from a pressure 15 to a cut-off position at predetermined points in the movement of the fluid-pressure motor, means co-acting between the second-named means and the operating member for maintaining the equilibrium of 20 the pressure device while said valve is being shifted, and means for adjusting the second-named means to effect a greater or less pressure variation acting on the pressure device 25 for a given movement of the fluid-pressure motor.

8. The combination with a fluid-pressure motor, of a pressure device and a controlling valve for operating the motor, an operating member for said valve, connections between said valve and said operating member 30 including a member pivoted to said operating member and arranged to be rocked by a second member which has a stationary pivoted bearing, compensating means operated from the fluid-pressure motor to rock the last-named member at predetermined points of the motor travel to effect the stopping of said motor, means co-acting between 35 said last-named member and the valve-operating member for effecting a counter-acting force to the pressure device in the opposite direction to the force exerted on the pressure device by the compensating means, and means for adjusting the compensating means 40 to effect a greater or less pressure variation of the pressure acting on the pressure device between the effective and the non-effective position of the controlling valve.

9. The combination with a fluid-pressure motor having a movable member, of a pressure device and a controlling valve for said motor, said controlling valve having a neutral position in which the motor is not effective and two effective positions for operating 45 the motor, said motor having an adjustable wedge connected with its movable member, an arm, the adjustable wedge having steps arranged to engage the arm for shifting the controlling valve to a neutral or non-effective 50 position, independent of the action of the

pressure device, at each stepped position on said wedge, and means operated by said arm to maintain a balanced condition of the pressure device while said valve is being shifted.

10. The combination with a fluid-pressure 70 motor, of a pressure controlling valve therefore, an operating lever for said valve, connections between said operating lever and said valve including a member pivoted to said operating lever, a second pivoted member having a stationary pivoted bearing and arranged to rock the first-named member, a spring co-acting between said second member and the operating lever, and means including an adjustable wedge for actuating said valve through said connections by the movement of the fluid-pressure motor independently of said operating lever.

11. The combination with a fluid-pressure 80 motor, of a pressure device and a controlling valve for operating said motor, said controlling valve having a neutral position in which it is not effective and two effective positions for operating the motor, an operating member for said valve, mechanical connections between said valve and said member including a member pivoted to the valve-operating member and arranged to be rocked on its fulcrum by a second member which has a stationary pivoted bearing, an arm for rocking the second-named member at predetermined points in the travel of said motor for returning the operating valve to a neutral position, and means including a spring co-acting 90 between the second-named member and the valve-operating member for maintaining the valve-operating member in a balanced condition while said arms are being rocked.

12. In a fluid system, means for controlling the fluid in the system, an operating member controlled in accordance with the condition of the fluid in the system for controlling the fluid-controlling means, a cam controlled by the fluid-controlling means, and means controlled by the cam for controlling the fluid-controlling means irrespective of the operation of the operating member.

13. In a fluid system, a motor for controlling the fluid in the system, a pressure-responsive device controlled in accordance with the condition of the fluid in the system, an operating member controlled by the pressure-responsive device for controlling the motor, a cam controlled by the motor, means controlled by the cam for controlling the motor irrespective of the operation of the operating member, the cam having means for accentuating the operation of the motor, and means for reacting on the pressure-responsive device to change the setting of the pressure-responsive device.

14. In a fluid system, a motor for controlling the fluid in the system, an element for controlling the motor, an operating member

- connected to the element, a pressure-responsive device controlled in accordance with the condition of the fluid in the system and connected to the operating member for effecting the operation of the element, a stepped compensating wedge connected to the motor, a lever adapted to be engaged by the steps of the wedge, a spring for counteracting the force exerted by the pressure-responsive device connected to the lever and to the operating member, and means connecting the lever to the element to effect the operation of the element irrespective of the operation of the operating member.
15. In combination, a motor, two elements having a relative neutral position in which they are ineffective and a relative effective position in which they control the operation of the motor, a beam having a pivot, a floating lever intermediately pivoted to the beam about the pivot, compensating means, a link connecting the lever with the elements on one side of the pivot, and means connecting the lever with the compensating means on the other side of the pivot, whereby the beam is adapted to relatively actuate the elements through the lever to the relative effective position irrespective of the operation of the compensating means and whereby the compensating means is adapted to return the elements through the lever to the relative neutral position irrespective of the operation of the beam.
16. In a pressure system, a motor for controlling the pressure in the system, a valve for controlling the motor, a scale beam for controlling the valve, a diaphragm controlled in accordance with the said pressure and connected to the scale beam for effecting the operation of the valve, a compensating wedge pivoted at one end of the motor and having multiple steps, and a member in contact with the stepped side of the said wedge for effecting the operation of the said valve by the said motor independently of the said diaphragm.
17. In a pressure system, means to control the pressure in the system, motive means for operating the controlling means, a controlling element for operating the motive means, a pressure-sensitive device connected to the pressure system for actuating the controlling element, a cut-off member having multiple steps operated by the motive means for rendering the controlling element ineffective independent of the operation of the pressure-sensitive device at each stepped position in the operation of the motive means, and adjustable means for effecting a greater or less pressure variation acting on the pressure-sensitive device between the limits of operation of the motive means.
18. In a fluid system, means for controlling the condition of the fluid in the system, two elements having a relative neutral position in which they are ineffective and a relative effective position in which they control the operation of the controlling means, a floating lever, means responsive to variations in the condition of the fluid in the system and connected with the floating lever and the elements for relatively actuating the elements through the floating lever to the relative effective position and means controlled by the first-named means and connected with the floating lever and the elements for relatively returning the elements to the relative neutral position at predetermined points in the operation of the first-named means.
19. In a fluid system, a motor for controlling the condition of the fluid in the system, two elements having a relative neutral position in which they are ineffective and a relative effective position in which they control the operation of the motor, a floating lever, means responsive to variations in the condition of the fluid in the system and connected with the floating lever and the elements for relatively actuating the elements through the floating lever to the relative effective position, and means for abruptly returning the elements to the relative neutral position at predetermined points in the operation of the motor to abruptly stop the motor at the predetermined points, the motor being adapted to operate freely between the predetermined points.
20. In a fluid system, a motor for controlling the condition of the fluid in the system, two elements having a relative neutral position in which they are ineffective and a relative effective position in which they control the operation of the motor, a beam, means responsive to variations in the condition of the fluid in the system for actuating the beam, a floating lever, means connecting the lever with the elements and with the beam, whereby the beam is adapted when actuated to relatively actuate the elements through the lever to the relative effective position, and means controlled by the motor and connected with the lever and the beam for relatively actuating the elements and the beam to relatively return the elements to the relative neutral position at predetermined points in the operation of the motor.
21. In a pressure system, a motor for controlling the pressure in the system, two elements having a relative neutral position in which they are ineffective and a relative effective position in which they control the operation of the motor, a device responsive to variations in the pressure of the system, a lever having three pivotal points, means connecting one of the pivotal points with the device, means connecting a second of the pivotal points with the elements, whereby the device is adapted to relatively actuate the elements to the relative effective position,

and means controlled by the motor connected with the third of the pivotal points and the device for relatively actuating the elements and the device to relatively return the elements to the relative neutral position at predetermined points in the operation of the motor.

22. In a pressure system, a motor for controlling the pressure in the system, two elements having a relative neutral position in which they are ineffective and a relative effective position in which they control the operation of the motor, a device responsive to variations in the pressure of the system, a lever having three pivotal points, means connecting one of the pivotal points with the device, means connecting a second of the pivotal points with the elements, whereby the device is adapted to relatively actuate the elements to the relative effective position, means controlled by the motor connected with the third of the pivotal points and the lever for relatively actuating the elements and the device to the relative neutral position at predetermined points in the operation of the motor, and means for rendering the said device ineffective to relatively actuate the elements in response to predetermined changes in the pressure of the system at each of the said predetermined positions.

23. In a pressure system, a motor for controlling the pressure in the system, two elements having a relative neutral position in which they are ineffective and a relative effective position in which they control the operation of the motor, a device responsive to variations in the pressure of the system, a lever having three pivotal points, means connecting one of the pivotal points with the device, means connecting a second of the pivotal points with the elements, whereby the device is adapted to relatively actuate the elements to the relative effective position, and means controlled by the motor connected with the third of the pivotal points and the device for relatively actuating the elements and the device to relatively return the elements to the relative neutral position at predetermined points in the operation of the motor, the last-named means comprising

a spring connected between the device and the motor.

24. In a pressure system, a fluid-pressure motor for controlling the pressure in the system, a valve for controlling the motor, the valve having a valve stem having a neutral position in which it is ineffective and two relative effective positions in which it controls the operation of the motor in opposite directions, a beam controlled in accordance with the pressure in the system, a lever having three pivotal points, means connecting one of the pivotal points with the beam, means connecting a second of the pivotal points with the stem, whereby the beam is adapted to actuate the stem to one or the other effective position in response to a variation in pressure, and means controlled by the motor connected with the third of the pivotal points and the beam for returning the stem to the neutral position at predetermined points in the operation of the motor, the last-named means comprising a spring connected between the beam and the motor.

25. In a pressure system, a motor for controlling the pressure in the system, two elements having a relative neutral position in which they are ineffective and two relative effective positions in which they control the operation of the motor in opposite directions, a device responsive to variations in the pressure of the system, a lever having three pivotal points, means connecting one of the pivotal points with the device, means connecting a second of the pivotal points with the elements, whereby the device is adapted to relatively actuate the elements through the lever to one or the other effective position in accordance with the variations in the pressure in the system, means controlled by the motor connected with the third of the pivotal points and the device for relatively actuating the elements and the device to relatively return the elements to the relative neutral position, the last-named means comprising a spring connected between the device and the motor, and means for ensuring a predetermined degree of operation of the motor before the motor is stopped.

JAMES LEWIS KIMBALL.
